WILLIAM A. SMITH, JR., OF PHILLIPSBURG, NEW JERSEY, ASSIGNOR TO INGERSOLL-RAND COMPANY, OF JERSEY CITY, NEW JERSEY, A CORPORATION OF NEW JERSEY

VALVE MECHANISM FOR ROCK DRILLS

Application filed November 22, 1928. Serial No. 321,133.

This invention relates to rock drills, but more particularly to a valve mechanism for rock drills of the fluid actuated type.

One object of the invention is to maintain one end of a valve of the oscillatory plate type firmly seated during the admission of pressure fluid into the cylinder. This result may be brought about by dividing the valve chamber into a plurality of pressure chambers, each one of which is in direct communication with a pressure fluid supply through separate and distinct channels, and the arrangement is such that when pressure fluid is being drawn from one pressure chamber into the cylinder, a pressure equal to line pressure will exist in the other pressure chamber to act on the valve for maintaining said valve firmly seated over the inlet passage.

20 Other objects will be in part obvious and in part pointed out hereinafter.

In the drawings illustrating the invention and in which similar reference characters refer to similar parts,

25 Figure 1 is a sectional elevation of so much of a rock drill as will serve to illustrate the invention,

Figure 2 is a transverse view taken through Figure 1 on the line 2—2 looking in the direction indicated by the arrows, and

30 Figure 3 is a similar view taken through Figure 1 on the line 3—3 looking in the direction indicated by the arrows.

Referring to the drawings, the invention 35 is shown embodied in a rock drill designated by A and comprising a cylinder B in which is disposed a reciprocating hammer piston C to deliver blows to a working implement (not shown). The cylinder B has a free 40 exhaust port D which is controlled by the piston C.

In the rearward end of the cylinder B is an enlarged bore E into which extends a boss F of a back head G seated on the rearward end of the cylinder A. The back head

G may be of a well known type and may be secured to the cylinder A in any well known manner as for instance by side bolts H disposed on opposite sides of the drill for clamping the casing parts of the drill securely together.

50 The back head G is provided with a throttle valve chamber J in which is disposed a throttle valve K of the rotary type having a lever L whereby said throttle valve may be manipulated. The throttle valve K has a central chamber O into which pressure fluid from a suitable source may be introduced, and in the side of the throttle valve is a port P which, in the open position of the 55 throttle valve, registers with a passage Q leading to a supply reservoir R in the front end of the back head.

The drill A is equipped with suitable mechanism for inducing a step by step rotary movement of the piston and consequently of the working implement through the medium of suitable chuck mechanism (not shown). The means provided for this purpose comprises a rifle bar S which is 60 slidably interlocked with the piston C and has a head T which carries spring pressed pawls U adapted to engage teeth V of a rotation ratchet W disposed in the bore E and serving as a seat for the back head G.

70 Disposed in the innermost end of the bore E is a suitable valve mechanism designated by X for controlling the admission of pressure fluid into the cylinder to actuate the piston C. The valve mechanism X constructed in accordance with the present invention comprises a pair of plates Y and Z. The plate Z forms a closure for the rearward end of the cylinder B and has a flat rearward surface which acts as a valve seat b and also as a seat for the plate Y. In addition to the functions described, the plate Z also acts as a closure for one side of a valve chamber c preferably formed entirely in the 75 80 85 90

plate Y for the reception of a distributing valve *d*.

The distributing valve *d* is of the oscillatory plate type and is preferably in the 5 form of a disk having tapered surfaces *e* and *f* at opposite ends converging from opposite sides of the valve to form wings *e'* and *f'*. The point of convergence of the 10 tapered surfaces *e* and *f* is on the transverse median line of the valve *d* thus forming apices *g* and *h* whereon the valve *d* is adapted to rock from one limiting position to another. It is in the plane wherein the 15 apices *g* and *h* lie that the valve attains its maximum thickness. The distance through the valve, at this point, however, is preferably small so that as the valve rocks from one limiting position to the other, the apices *g* and *h* will travel through only a small arc. 20 The valve chamber *c* is provided with an intermediate restricted portion *j* formed in this instance by an integral rib *j'* on the plate Y. The restricted portion *j* is of a depth substantially equal to the thickness of 25 the valve at the point of the apices so that said apices *g* and *h* will be in body contact with the bounding surface of the restricted portion *j*, as for instance, with the surface *b* of the plate Z and with a surface *k* of the 30 rib *j'* which overlies the plate Z. The rib *j'* also serves as a stop for the valve and opposite wings *e'* and *f'* of the valve are adapted to seat alternately on the surfaces *b* and *k*.

35 The rib portion *j'* is preferably formed with an enlarged central portion *v* and reduced neck portion *v'* defining the curved inner edges of a pair of arcuate slots separated at their terminal ends by the neck 40 portions of the rib *j'* to form separate pressure chambers *o* and *p* into which pressure fluid from the supply reservoir R may be introduced through supply passages *q* formed in this instance in the rotation 45 ratchet W. The pressure chambers *o* and *p* may be in the form of arcuate recesses of sufficient area to accommodate a substantial volume of pressure fluid and may be so located that they overlie a substantial area or 50 areas of the outer portion of the valve *d* and preferably also over the inlet openings of the inlet passages *r* and *s* leading to the rearward and forward ends respectively of the cylinder B.

55 As is customary in valves of the type illustrated, the body portion of the valve *d* is of somewhat smaller diameter than the valve chamber wherein it is disposed to permit a free flow of pressure fluid over a substantial 60 portion of the raised end of the valve. In certain cases where uniformity of pressure throughout the valve chamber is not considered objectionable, the valve may be in the form of a true disk and clearance will 65 therefore exist between all points of the

edge of the valve and the adjacent surface of the valve chamber. In the present instance, however, it is desirable to prevent such free communication between the several portions of the valve chamber, as for 70 instance, between the pressure chambers *o* and *p* and to this end the valve *d* is provided on its edge or periphery and in the plane of the apices *g* and *h* with projections *t* of suitable width and having partly cylindrical 75 surfaces *u* which bear against the wall of the valve chamber *c* for preventing the flow of pressure fluid from one pressure chamber to another at this point.

The operation of the device is as follows: 80 Pressure fluid flowing from the throttle valve K into the supply reservoir R will flow through the supply passages *q* into both of the pressure chambers *o* and *p*. With the left hand end of the valve raised, as illustrated, pressure fluid will then flow through the inlet passage *r* into the rearward end of the cylinder to impel the piston C forwardly. During this movement of the piston, 85 the air in the front end of the cylinder will be compressed and will flow through the inlet passage *s* to act against the tapered surface *f* of the seated portion of the valve to assist the suction of the pressure fluid flowing over the raised end of the valve to 90 tip the valve to its other limiting position immediately after the piston C overruns the free exhaust port D, in which case there is an abrupt drop in pressure in the rearward end of the cylinder. 100

During the time, however, that pressure fluid is being admitted to the rearward end of the cylinder to drive the piston C forwardly, the pressure in the pressure chamber *p* will be of somewhat less value than 105 line pressure, due to the expansion of the pressure fluid, not only in the cylinder but also in the pressure chamber *p*. Inasmuch that the pressure chamber *p* is completely separated from the pressure chamber *o* the drop in pressure in the chamber *p* resulting 110 during the admission of pressure fluid into the cylinder will not be communicated to the pressure fluid existing in the pressure chamber *c*. Therefore the entire surface *e* of the seated end of the valve will be exposed to full line pressure, or in other words, 115 to a pressure somewhat in excess of that existing in the pressure chamber *p*. As a result of this feature the valve will be held 120 firmly in its limiting position and the tendency of the seated end of the valve to be repeatedly raised from its seat by the suction created by the pressure fluid flowing over the raised end of the valve will be 125 eliminated. The piston C will thus be free to deliver a heavy blow against the working implement without having some of its force absorbed by a cushion of live pressure fluid in the front end of the cylinder as would 130

be the case were the valve *d* allowed to tremble on its seat.

About the time the piston *C* is ready to deliver its blow to the working implement, the compression in the inlet passage *s* and the air flowing over the raised end of the valve *d* will tilt the valve to its other extreme position. In the new position of the valve, pressure fluid will flow over the right hand end of the valve through the inlet passage *s* into the cylinder *B* to drive the piston *C* rearwardly. During this stroke as during the forward stroke of the piston, the drop in pressure in the pressure chamber *c* resulting from the admission of pressure fluid into the cylinder will also be prevented from being communicated to the pressure existing in the pressure chamber *p* by the valve *d*, that is, by the apices *g* and *h* and the projections *u* which effectively prevent communication between the pressure chambers through the valve chamber.

By maintaining the valve firmly seated during the rearward stroke of the piston, it will be impossible for the pressure fluid to leak or flow into the rearward end of the cylinder to augment the compression created by the piston and the piston *C* is therefore capable of advancing rearwardly the full distance of its nominal stroke instead of being reversed immediately after the exhaust port *D* is uncovered. This feature of course results in greater drilling efficiency than would be the case if the piston were reversed before running the full course of its nominal stroke.

During the rearward stroke the piston will uncover the exhaust port *D* to open the front end of the cylinder and the space beneath the raised end of the valve to the atmosphere and the compression created by the piston on the rearward end of the cylinder and the suction of the air flowing over the raised end of the valve will then again actuate the valve to its initial position.

I claim:

1. In a fluid actuated rock drill, the combination of a cylinder and a reciprocatory piston, a valve chest comprising a pair of plates one of which plates is recessed to form a cylindrical valve chamber, a valve seat on one of the plates, a rib on the other plate extending across the valve chamber to form an intermediate restricted portion in the valve chamber, said rib having an enlarged center portion and reduced neck portions thereon defining the curved inner edges of a pair of arcuate slots separated at their terminal ends by the neck portions of the rib to form separate pressure chambers, inlet passages leading from the pressure chambers to the cylinders, an oscillatory disc distributing valve in the valve chamber controlling the inlet passages and having the major portion of its periphery spaced from

the peripheral bounding surface of the valve chamber to permit the passage of pressure fluid to the inlet passages, said valve having an apex at each end to bear on the valve seat and the rib for preventing the flow of pressure fluid from one pressure chamber to the other through the restricted portion. 70

2. In a fluid actuated rock drill, the combination of a cylinder and a reciprocatory piston, a valve chest comprising a pair of plates one of which plates is recessed to form a cylindrical valve chamber, a valve seat on one of the plates, a rib on the other plate extending across the valve chamber to 75 form an intermediate restricted portion, said rib having an enlarged center portion and reduced neck portions thereon defining the curved inner edges of a pair of arcuate slots separated at their terminal ends by the neck portions of the rib to form separate pressure chambers, said rib presenting a relatively broad flat surface to act as a valve stop, inlet passages leading from the pressure chambers to the cylinder, an oscillatory disc distributing valve in the valve chamber controlling the inlet passages, and having the major portion of its periphery spaced from the peripheral bounding surface of the valve chamber to permit the 80 passage of pressure fluid to the inlet passages, an apex at each end of the valve to bear on the valve seat and the rib, said valve being uniformly tapered from the apices to the periphery at each side of the 85 valve to form wings adapted to seat alternately on the valve seat and the rib for preventing the flow of pressure fluid from one pressure chamber to the other through the restricted portion. 90

3. In a fluid actuated rock drill, the combination of a cylinder and a reciprocatory piston, a valve chest comprising a pair of plates one of said plates being recessed to form a cylindrical valve chamber, a valve seat on one of the plates, a rib on the other plate extending diametrically across the valve chamber to form an intermediate restricted portion in the valve chamber, said rib having an enlarged center portion and reduced neck portions thereon defining the curved inner edges of a pair of arcuate slots separated at their terminal ends by the neck portions of the rib to form separate pressure chambers, said rib presenting a relatively broad flat surface to act as a valve stop, inlet passages leading from the pressure chambers to the cylinder, an oscillatory disc distributing valve in the valve chamber controlling the inlet passages and having the major portion of its periphery spaced from the peripheral bounding surface of the valve chamber to permit the passage of pressure fluid to the inlet passages, an apex 95

seat and the rib, wings on opposite sides of the apices being uniformly tapered from the apices to the periphery and adapted to seat alternately on the valve seat and the rib, and projections on opposite sides of the valve lying in the plane of the apices and having partly cylindrical surfaces to cooperate with the peripheral bounding surfaces of the valve chamber for preventing the flow of pressure fluid from one pressure chamber to another through the valve chamber.

In testimony whereof I have signed this specification.
